UNITED STATES PATENT OFFICE.

RALPH S. OTIS, OF WEST HARTFORD, CONNECTICUT.

RAZOR-STROPPING MACHINE.

1,080,776.

Specification of Letters Patent.

Patented Dec. 9, 1913.

Application filed February 4, 1913. Serial No. 746,147.

To all whom it may concern:

Be it known that I, RALPH S. OTIS, a citizen of the United States, residing at West Hartford, in the county of Hartford and 5 State of Connecticut, have invented a new and useful Razor-Stropping Machine, of which the following is a specification.

My invention relates to razor stropping machines of the class through which a strop 10 is threaded and is to be alternately pulled at its ends, and a blade-holder located between the reaches of the strop and adapted to alternately carry the blade thereto as said reaches are alternately pulled outwardly 15 in line with their length, the blade moving to one reach as it is pulled outwardly and to the other reach when it is pulled outwardly, and said invention consists in the novel features hereinafter described, and 20 particularly pointed out in the claims.

The object of the invention is to provide an efficient stropping machine of the class referred to and more particularly a stropping machine possessing in addition to 25 means for rocking the blade-holder from one side to the other as the alternate reaches of the strop are pulled, novel mechanism for causing the strop to travel along the razor blade lengthwise, said motion, combined with the motion of said strop from 30 back to edge of the razor blade while the blade is against the alternately outwardly moving reaches of the strop, causing a diagonal stropping of the blade, thereby giving 35 substantially the same treatment that it would receive if stropped by hand, but with a more accurate and uniform motion.

The prime purpose of the invention is to provide a stropping machine which is simple 40 in construction, efficient and durable.

The invention will be readily understood from the detailed description which follows, reference being required to the accompanying drawings, in which:—

45 Figure 1 is a substantially central vertical longitudinal section through a stropping machine embodying my invention, the strop being partly broken away and the section being on the dotted line 7—7 of Fig. 2. Fig. 50 2 is an end view of the machine. Fig. 3 is an enlarged cross sectional view of the machine. Fig. 4 is a top view of the machine.

In the drawings, 12 designates the frame of the machine, 13 a carriage, 14 the strop, 55 15—15 a rotary and endwise movable friction-roller, 16—16 the ends of said roller

journaled in the ends of the carriage 13, 17 a sleeve, part of the device for moving the blade-holder, 18 a spirally grooved shaft, stationary in said frame, 19 a rocking shaft, 60 journaled at its ends in said frame, 20 a lug extending from the rocking shaft, 21 a blade-holder rigidly attached to said rocking shaft, 22—23 centering springs which pass through openings in the carriage 13 65 and are loosely secured in the frame 12.

The frame 12 is provided at the top with a drawn out section 24, to receive a loop 25, by which the machine may be attached to any convenient restraining object. Holes 70 are pierced in the ends of said frame for the ends of the spirally grooved shaft 18, the rocking shaft 19, and the centering springs 22—23.

The friction-roller 15—15 is a plain 75 smooth roller, having a portion reduced in diameter for the sleeve 17, said roller encompassing the spirally grooved shaft 18. Said roller 15—15 may rotate in either direction, and when rotated will travel endwise along the spirally grooved shaft 18, by means of nuts or studs within said roller 15—15 being engaged in the spiral groove of the shaft 18. The sleeve 17 snugly though freely encircles a reduced portion of 80 the roller 15—15. Said sleeve 17 is provided with extending lugs 36—36, and is part of the device for moving the blade-holder, as hereinafter described.

The rocking shaft 19 is journaled at its 90 ends in the ends of frame 12, said shaft having an extending lug 20, to engage the lugs 36—36 of the sleeve 17, and means provided to attach the blade-holder 21 to said shaft 19.

The blade-holder 21 comprises a pair of 95 converging jaws of known character, and a spring 37 as usual, and the ends of said blade-holder are formed to be rigidly attached to the rocking shaft 19.

The carriage 13 is provided with bearings 100 for the friction-roller 15—15, and bearings that are a slid-able fit on the rocking shaft 19. Openings for the centering springs 22—23, and openings 26 to allow said carriage to travel endwise of the blade-holder 21. Also 105 the usual studs or pins, 27, 28, 29, 30, 31, 32, for guiding the reaches of the strop 14.

The centering springs 22—23, shown in the drawing to be flat, but which may be of round wire, at or near their center are in contact with lug 20, one of said springs on either side of said lug 20, said springs 110

22—23 being held in position near their ends in frame 12.

The strop 14 is threaded through the carriage 13, and is folded over the friction-5 roller 15—15 and the sleeve 17; the rocking shaft 19, the blade-holder 21, and the centering springs 22—23, being located midway between the reaches of said strop 14.

The following is a detailed description 10 of the construction of the friction-roller 15—15, and the mechanism for moving the blade-holder 21: 33—33 are tubes of cylindrical form. 34—34 is a tube of cylindrical form, snugly fitting within tubes 33—33 and 15 firmly attached to said tubes. 35—35 are nuts within tube 34—34 and firmly attached to said tube. The ends of tube 34—34 extend beyond the ends of tubes 33—33 and 20 form journals to fit the bearings in the carriage 13. 17 in the drawing is a sleeve snugly fitting the tube 34—34, but allowing 25 said tube to move freely, with a rotary motion, in said sleeve 17. Lugs 36—36 extend from sleeve 17 and engage lug 20 which extends from the rocking shaft 19. The rocking shaft 19, the lug 20 and the blade-holder 21 are firmly attached to each other. Therefore as the lug 20 is normally held in a central 30 position between the reaches of the strop 14, by the centering springs 22—23, the blade-holder is also held in a central position between the reaches of said strop.

In the employment of the machine, the razor blade, or the usual safety-blade-holder 35 containing a safety razor blade, will be inserted endwise between the jaws of the holder 21, and the reaches of the strop 14 will be alternately pulled to effect the strop-40 ping of the blade. A pull downwardly on the right hand reach of the strop 14, see Fig. 3, will cause the opposite reach of the strop to move upwardly and over the roller 15—15 and thereby rotate the same, and through the nuts 35—35 cause the roller 15—15 to 45 travel endwise along the stationary spirally grooved shaft 18, and at the same time the movement of the strop 14 on the sleeve 17, will cause the lugs 36—36 to take the position shown in Fig. 3 and rock the blade-holder 21 to carry and hold the blade 38 in contact with said right hand reach of the strop, the pressure of the blade being governed by the force of the pull on said reach and therefore controllable by the operator.

50 During the downward pull on the right hand reach of the strop 14 against the edge of the blade 38, and the rotation of the roller 15—15, said roller rotating on, and at the same time moving endwise along the spirally grooved shaft 18, will cause the carriage 13 and strop 14 to travel in a line corresponding to the endwise travel of the roller 15—15, by means of the bearings of said carriage 13 on the ends of the roller 55 15—15. Therefore the combined rotary and

endwise motion of the roller 15—15 will cause a diagonal motion of the strop 14 across the razor blade, stropping said razor blade in the most approved and effectual manner.

When the pull on the right hand reach of the strop is released, the left hand spring 22 will instantly move the blade-holder to withdraw the blade from said reach, and thereupon when the left hand reach of the strop, see Fig. 3, is pulled downwardly, the roller 15—15 will be given a reverse rotation thereby, and the lugs 36—36 will be, by action of the strop on the sleeve 17, reversed in position; that is, turned from the position on the left shown in Fig. 3, to a position on the right, and in their said movement, said lugs 36—36 will cause the blade-holder to carry the blade to said left hand reach of the strop being pulled downwardly. During the reverse rotation of the roller 15—15, while the left hand reach of the strop is being pulled downwardly, said roller will travel endwise in a reverse direction to that effected during the downward movement of the right hand reach of the strop. Therefore as the alternate reaches of the strop are pulled, the lugs 36—36 are turned to move the blade-holder to that reach of the strop moving outwardly, and the roller is rotated to effect the endwise travel of said roller, causing the carriage 13 and strop 14 to move along said blade-holder lengthwise, said blade-holder being turned to one side and then the other, and said carriage 13 caused to travel in one direction and then the other as the reaches of the strop are alternately pulled outwardly.

I have shown and described in detail the best form of the invention known to me, but I do not of course limit my invention to all the details presented, for I am aware that such details may be modified in many respects without departing from my invention.

I claim as my invention and desire to secure by Letters Patent:

1. A razor stropping machine comprising a frame, a spirally grooved shaft, stationary in said frame, a rocking shaft journaled at its ends in said frame, said shaft having a lug extending toward the spirally grooved shaft, a razor blade-holder rigidly attached to said rocking shaft, a friction roller encompassing the spirally grooved shaft, said roller having nuts or studs engaged in the spiral groove of said shaft to effect endwise travel of said roller during its rotation, a carriage with bearings fitting the ends of said roller, a strop folded over said roller, shafts and holder, and guided in said carriage, and means to be actuated by the strop for turning the blade-holder to the reach of the strop pulled outwardly; substantially as set forth.

2. A razor stropping machine comprising

a frame, a spirally grooved shaft stationary in said frame, a rocking shaft journaled in said frame, said shaft having a lug extending toward the spirally grooved shaft, a 5 blade holder firmly attached to said rocking shaft, a movable friction roller surrounding a portion of the spirally grooved shaft, said roller having a part engaged in the spiral groove of said shaft to effect endwise 10 movement of said roller during its rotation, a sleeve freely fitting a reduced portion of said roller, said sleeve having lugs to engage with the lug extending from the rocking shaft, thereby transmitting motion to 15 the rocking shaft, and through said rocking shaft an oscillating motion to the blade holder, a carriage with bearings fitting the friction roller and rocking shaft, a strop folded over said roller, sleeve, shafts and 20 holder, and guided in said carriage, said strop when actuated, causing the blade holder to turn to the reach of the strop pulled outwardly; substantially as set forth.

3. A razor stropping machine comprising 25 a frame, a locking shaft with firmly attached razor-blade holder, in said frame, a spirally grooved, stationary shaft in said frame, a friction roller somewhat shorter than the frame, surrounding a portion of 30 said shaft, an operative connection between the roller and shaft, a sleeve fitting a portion of said roller, but allowing said roller to rotate within the sleeve, an oper-

ative connection between said sleeve and rocking shaft, a carriage mounted on the 35 roller and guided in the frame, a strop threaded through said carriage and folded over the blade holder, shafts and roller, said strop when reciprocated, actuating the roller, thereby causing the carriage to reciprocate within the frame, through the connection of said carriage and roller, substantially as set forth.

4. A razor stropping machine comprising a frame, a rocking shaft with firmly attached razor-blade holder, in said frame, a spirally grooved, stationary shaft in said frame, a movable friction roller surrounding a portion of said shaft, an operative connection between the roller and shaft, a 50 sleeve fitting a portion of said roller, an operative connection between the sleeve and rocking shaft, a reciprocatory carriage mounted on the friction roller and slideable on the rocking shaft, a strop threaded 55 through the carriage and folded over the blade holder, shafts and roller, said strop when actuated, moving diagonally within the frame, through the rotary and simultaneous endwise movement of the friction 60 roller, thereby causing a diagonal stropping of the razor blade, substantially as set forth.
